UNITED STATES PATENT OFFICE.

RICHARD DEMPSEY, OF PHILADELPHIA, PENNSYLVANIA.

IMPROVEMENT IN WICKER-COVERED BOTTLES.

Specification forming part of Letters Patent No. 147,485, dated February 17, 1874; application filed January 10, 1874.

To all whom it may concern:

Be it known that I, RICHARD DEMPSEY, of Philadelphia, Pennsylvania, have invented an Improvement in Wicker-Covered Bottles and Demijohns, of which the following is a specification:

Convenience and the exigencies of business very frequently require druggists, liquor-dealers, and others to loan bottles and demijohns to their customers for temporary use, or to put such vessels temporarily out of their keeping—as, for instance, when they are deposited for carriage from one place to another, or for other purposes. From these sources much loss and inconvenience arise.

Wicker-covered vessels frequently also require to be permanently marked with labels descriptive of the nature of their contents, and this has hitherto been done by a tag, which is easily displaced and lost.

My improvement is designed to obviate the difficulties referred to; and it consists in forming an opening of the required size and shape in the wicker-work, and fastening to the body of the covered vessel a label of glass, metal, paper, wood, or other material containing the name and address of the owner, the name of the contents of the vessel, and ornamental devices, one or all, the edge of the wicker-work around the edge of the label-space being preferably caused to project above the surface of the label.

In the course of my experiments I have found that the opening in the wicker-work could not be practically made without the introduction of some material not liable to be shrunk or warped by the moisture in the rattan or willow, which require to be made wet when worked, in order that they may have the requisite pliability. The top and bottom of the opening I have found to be sufficiently sustained by the stakes against this warping action; but the sides I have found to twist, draw back, or shrink away as they dry, so as to destroy the outline of the opening, and, of course, render it necessary to have an irregular-shaped label. To avoid this objection, and to obtain a regular outline, I re-enforce the stakes at the sides of the opening by strips of

metal or pieces of wire extending across and above and below the opening, as represented in the drawing. The upper and lower ends of these re-enforcing-wires, being held firmly in the wicker-work, resist the warping tendency of the sides of the opening, and hold them to their proper places.

In the drawings, Figure 1 is a perspective view of a wicker-covered bottle embracing said improvement; Fig. 2, a part of a horizontal section of the same through the label.

a represents the label, which is attached to the body of the bottle with cement. *b* is the wicker covering, which projects above or beyond the level of the label, as shown in Fig. 2. *c* and *d* are two wires, preferably, but not necessarily, of steel, inserted into the wicker covering along or near the sides of the label-space, for stiffening and holding up the edges of the wicker, which, without some such support, sags when damp.

Instead of cementing the label, when of wood or metal, to the body of the covered vessel, it may be fastened in its place by means of wires or points projecting from the edges of the label, or by making the label with a double edge, which can be caused to clasp the edges of the wicker covering around the label-space, or by perforating or slotting the edges of the label, and passing strands of the wicker through the perforations or slots.

I claim—

1. A bottle or demijohn provided with a wicker-work covering, the latter constructed with an opening through its side, for the display of a label, and the sides thereof projecting in front of the surface of the label, to protect the same, substantially as set forth and shown.
2. The wicker covering *b*, provided with an opening in its side, for the display of a label, the sides of the said opening being stiffened by metallic pieces *c* and *d*, substantially as and for the purpose set forth and shown.

RICHARD DEMPSEY.
